(57) **CLAIM**

The ornamental design for a freezable hailstone model substantially as shown and described.

DESCRIPTION

FIG. 1 is a perspective view of a first embodiment of the freezable hailstone model;

FIG. 2 is a front view of the freezable hailstone model of FIG. 1;

FIG. 3 is a rear view of the freezable hailstone model of FIG. 1;

FIG. 4 is a left view of the freezable hailstone model of FIG. 1;

FIG. 5 is a right view of the freezable hailstone model of FIG. 1;

FIG. 6 is a bottom view of the freezable hailstone model of FIG. 1;

FIG. 7 is a top view of the freezable hailstone model of FIG. 1;

FIG. 8 is a perspective view of a second embodiment of the freezable hailstone model;

FIG. 9 is a front view of the freezable hailstone model of FIG. 8;

FIG. 10 is a rear view of the freezable hailstone model of FIG. 8;

FIG. 11 is a left view of the freezable hailstone model of FIG. 8;

FIG. 12 is a right view of the freezable hailstone model of FIG. 8;

FIG. 13 is a bottom view of the freezable hailstone model of FIG. 8; and,

FIG. 14 is a top view of the freezable hailstone model of FIG. 8.

The broken lines illustrate portions of the freezable hailstone model that form no part of the claimed design.

1 Claim, 14 Drawing Sheets
